(57) **CLAIM**

We claim the ornamental design for a baking pan, as shown and described.

DESCRIPTION

FIG. 1 is a perspective view of a baking pan according to the new design;

FIG. 2 is a top view of the baking pan shown in FIG. 1;
FIG. 3 is a front view of the baking pan shown in FIG. 1, the rear view being identical thereto;

FIG. 4 is a left side view of the baking pan shown in FIG. 1, the ride side view being identical thereto; and,

FIG. 5 is a bottom view of the baking pan shown in FIG. 1.
